Filed June 27, 1962, Ser. No. 70,712

Term of patent 14 years

(Cl. D34—5)

FIG 1.

FIG. 2

FIG. 3

FIG. 4

FIG. 1 is a perspective view of a bowling scorer table top showing my new design, this view being taken from the front and somewhat above and to the right of the console.

FIG. 2 is a fragmentary view of the bowling scorer table top of FIG. 1 taken on the line 2—2 of FIG. 3 and showing in elevation the score printer unit and the automatic scoring system controls of the console.

FIG. 3 is a side elevational view of the bowling scorer table top of FIG. 1.

FIG. 4 is a rear elevational view of the bowling scorer table top of FIG. 1 taken on the line 4—4 of FIG. 3.

The broken line showings of a support and of a score card are for illustrative purposes only.

I claim:

The ornamental design for a bowling scorer table top, as shown and described.
